United States Patent Office

Des. 185,524
Patented June 16, 1959

185,524

FORK OR SIMILAR ARTICLE OF FLATWARE

John P. Young, Bronxville, N.Y., and Charles A. Arnold, Providence, R.I., assignors to Lyon Incorporated, Detroit, Mich., a corporation of Delaware

Application April 22, 1958, Serial No. 50,578

Term of patent 14 years

(Cl. D54—12)

Fig. 1

The essential features of our design reside in the handle portion shown in the full lines on the drawing. The appearance of the opposite face of the handle not shown is plain.

We claim:

The ornamental design for a fork or similar article of flatware, substantially as shown and described.
